F. HARDINGE.
OIL BURNER.
APPLICATION FILED MAY 16, 1921.

1,417,520.

Patented May 30, 1922.

Inventor:

Franklin Hardinge

Williams Bradbury
See & H. Caleb Atty

UNITED STATES PATENT OFFICE.

FRANKLIN HARDINGE, OF CHICAGO, ILLINOIS.

OIL BURNER.

1,417,520.

Specification of Letters Patent. Patented May 30, 1922.

Application filed May 16, 1921. Serial No. 470,209.

To all whom it may concern:

Be it known that I, FRANKLIN HARDINGE, a citizen of the United States, and resident of Chicago, in the county of Cook and State 5 of Illinois, have invented a certain new and useful Improvement in Oil Burners, of which the following is a full, clear, concise, and exact description, reference being had to the accompanying drawings, forming a 10 part of this specification.

My invention relates to improvements in oil burners and is particularly concerned with improvements in that type of oil burner comprising an outwardly flaring rotary atomizing nozzle to which the fuel to be burned is supplied by a suitable standpipe in such 15 manner that it will spread over the inner surface of the atomizing nozzle in a thin film and be thrown from the edge of the 20 nozzle in a fine spray suitable means being provided for mixing the oil spray thus formed with sufficient air to form a combustible mixture.

Experience has demonstrated that the inner surface of the atomizing nozzles of oil burners of the type described will, after continued use, become more or less coated with a deposit of carbonized oil and impurities present in the fuel being burned. To secure 25 the best results, it is necessary to remove this coating from time to time, and one of the objects of my present invention is to provide a burner of such construction as to permit the inner surface of the atomizing nozzle 30 to be easily and quickly cleaned of this deposit.

Another object of my invention is to provide a novel means for cleaning the inner surface of the atomizing nozzle.

Further objects will appear as this description progresses, reference being had to the accompanying drawings in which—

Figure 1 is a central longitudinal section through the head of an oil burner involving my invention, portions of the furnace being shown in section, and

Figure 2 is a horizontal transverse section through my improved burner taken on line 2—2 of Figure 1.

In both of the views, similar characters will be used for referring to similar parts.

In my co-pending application, Serial No. 380,794 filed May 12, 1920, I have illustrated and described an oil burner comprising a cup 5 into which the fuel oil is discharged through the standpipe 6 and on the upper

end of which is mounted an outwardly flaring atomizing nozzle 7 from the knife edge 8 of which the oil is discharged in a finely divided or atomized condition. The cup 5 is mounted upon a rotary hollow shaft 9 and means, not shown, are provided for rotating this shaft at high speed. The construction of this atomizer and the means for rotating the nozzle are fully and clearly described in my co-pending application referred to and further description thereof appears to be unnecessary.

The particular construction of the standpipe and the cap or bell 10, over which the oil is discharged from the standpipe and from which it is discharged into the centrifugal separator comprising the cup 5 are described and claimed in my co-pending application, Serial No. 470,211, filed May 16, 1921. Since these details of construction do not form any part of my present invention, further description thereof is omitted.

A cap comprising top and bottom sections 11 and 12 is supported upon the upper end 30 of the standpipe 6, the upper end of the standpipe being reduced in cross-section to form a shoulder 13 upon which the lower end of the sleeve 14, forming a part of the bottom section 12 of the cap, rests. The lower section comprises an upwardly extending outwardly flaring lug or projection 15 which is provided with a curved channel 16 for receiving one end of the cleaning device 17 which will be referred to later on.

The extreme upper end of the standpipe 6 is provided with a flattened face 18. A washer 19 surrounds the upper end of the standpipe and has an opening therethrough which conforms to the flattened face 18 of the standpipe 30 so as to lock the washer 19 against rotation. The washer 19 is provided with two arcuate slots 20 and 21 for receiving the shank of a screw 22, the lower end of which is received in a suitable screw-threaded opening 23 formed in the wall of the lower section 12 of the cap. By means of this slot and screw connection between the lower section 12 of the cap and the washer 19, the cap can be adjusted relatively to the standpipe so as to make the channel 16 accessible from practically any desired point, thus making it easy for the operator to insert the cleaning device 17.

The upper section 11 of the cap is, in general, cylindrical in form and its lower edge is offset as shown at 24 to provide a retain-

2

ing flange for co-acting with the upper edge of the section 12 to lock the section 11 in place. One side of the section 11 is cut away to provide a recess for the outwardly flaring projection 15, as shown in Figure 1. The cleaning device 17 is preferably formed of a heavy wire or light rod which is preferably square in cross-section and the inner end of which is curved, as shown at 25 to provide a curved surface for contacting with the inner surface of the atomizing nozzle: the outer end of the wire may be curved as shown at 26 to provide a suitable handle. In cleaning the atomizing nozzle, the supply of oil to the nozzle is first shut off, the burner is then caused to rotate and the operator inserts the cleaning device into the burner through the channel 16 in the lower section 12 of the cap and then moves the cleaner so as to bring the curved portion 25 into contact with all portions of the inner surface of the burner. The cleaning device acts as a scraper to remove the deposit of carbon and impurities from the burner thus leaving it in condition for further operation. During the cleaning process, one side or the other of the channel 16, depending upon the direction of rotation of the atomizing nozzle will act as a stop to hold the cleaning device from being carried along by the atomizing nozzle.

While I have described the details of construction of the preferred embodiment of my invention, it is to be clearly understood that my invention is not limited to these details of construction, but is capable of other adaptations and modifications within the scope of the appended claims.

Having thus described my invention, 40 what I claim is:

1. An oil burner comprising an outwardly flaring rotary atomizing nozzle, a standpipe projecting upwardly into said atomizing nozzle for supplying oil thereto and a heat insulating cap supported by said standpipe and projecting downwardly into said nozzle,

said cap having a slot formed in one side thereof for receiving a device for engaging the inner surface of said nozzle.

2. An oil burner comprising an outwardly flaring rotary atomizing nozzle, a standpipe projecting upwardly into said atomizing nozzle for supplying oil thereto and a cap supported by said standpipe and projecting downwardly into said nozzle, said cap having an opening formed in one side thereof for receiving a device for engaging the inner surface of said nozzle.

3. An oil burner comprising an outwardly flaring rotary atomizing nozzle, a standpipe projecting upwardly into said nozzle for supplying oil thereto, and means secured to the upper end of said standpipe for holding a cleaning device in engagement with the inner surface of said atomizing nozzle.

4. An oil pipe comprising an outwardly flaring rotary atomizing nozzle and means supported adjacent the discharge end of said nozzle for holding a cleaning device in engagement with the inner surface of said atomizing nozzle and from movement in the direction of rotation of said nozzle.

5. An oil pipe comprising a rotary atomizing nozzle and means supported adjacent the discharge end of said nozzle for holding a cleaning device in engagement with the surface of said atomizing nozzle and from movement in the direction of rotation of said nozzle.

6. An oil pipe comprising a rotary atomizing nozzle and means supported in axial alignment with said nozzle for holding a cleaning device in engagement with the surface of said atomizing nozzle and from movement in the direction of rotation of said nozzle.

In witness whereof, I hereunto subscribe my name this 11th day of May, 1921.

FRANKLIN HARDINGE.
